UNITED STATES PATENT OFFICE.

WILLIAM C. TOELLNER, OF BUNCETON, MISSOURI.

ATTACHMENT FOR RADIATORS.

Application filed June 18, 1921. Serial No. 478,698.

To all whom it may concern:

Be it known that I, WILLIAM C. TOELLNER, a citizen of the United States, residing at Bunceton, in the county of Cooper and State of Missouri, have invented new and useful Improvements in Attachments for Radiators, of which the following is a specification.

This invention relates to a cover member for the front part of radiators and motor vehicles and the like, the principal object of the invention being to provide means, controlled from the driver's seat, for regulating the amount of air passing through the radiator or for entirely shutting off the flow of air through the radiator.

Another object of the invention is to provide means whereby the air opening in the device is so controlled that the lower part thereof will be last to open and the first to close, thus preventing the water in the radiator from freezing at the bottom thereof, where the water is the coolest.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a side view of a portion of an automobile showing my invention in use.

Figure 2 is a front view.

Figure 3 is an enlarged vertical sectional view through the invention.

Figure 4 is a section on line 4—4 of Figure 3.

Figures 5 and 6 are detail views.

In these views 1 indicates the cover member which is adapted to be secured to the front part of the radiator A by means of the bolts 2 which pass between the water tubes of the radiator and are provided with suitable washers and nuts for securing the parts in position. As shown the cover member is provided with an opening 4 through which air can pass to come in contact with the water tubes of the radiator. The lower part of the cover member extends a considerable distance below the bottom of the radiator, as shown at 5, so that the said lower

part of the radiator is well protected by the device. A pair of guiding grooves 6 are formed in each side wall of opening 4, one groove being of greater length than the other and said grooves receive the ends of the shutters 7 and 7'. The lower shutter 7' works in the short grooves and the upper shutter 7 works in the long grooves. Strips 8 of leather or the like may be fastened to the ends of the shutters to prevent them from rattling in the grooves. The upper shutter has its lower edge bent into hook shape, as shown at 9, and the lower shutter has its upper edge bent inwardly and downwardly into hook shape, as shown at 10, and these two bent edges are adapted to engage with each other so that the upper shutter will pull upwardly the lower shutter as said upper shutter is moved upwardly to close the opening. The lower edge of the lower shutter is rolled around a wire, as shown at 11, and the lower edge of opening 4 is also rolled around a wire, as shown at 12, and these parts coming in contact with each other when the shutters are fully closed will thus prevent upward movement of the shutters. The upper edge of the opening 4 may also be rolled around a wire as shown at 13. The upper edge of the upper shutter 7 is bent outwardly at right angles, as at 14, and this part will engage the lower edge of the opening 4 when the shutters are in fully open position, thus closing the space between member 1 and the radiator and it will also engage the upper edge of opening 4 when the shutters are fully closed.

A cable 15 is connected with the upper edge of the upper shutter 7 and passes over a small pulley 16 carried by the member 1 and passes through a hole in the dash where it is connected with a chain 17 which is adapted to engage with a holder 18 so that the shutters can be held entirely closed or in open or partly open condition. This holder is provided with a hook 19 and with an opening 20 having a reduced lower portion for receiving the links of the chain so that a chain can be slackened to any desired extent to permit the shutters to be placed at any desired position.

From the above it will be seen that the amount of air passing through the radiator can be readily adjusted from the driver's seat and that the said air can be entirely shut off when desired. It will also be seen that the upper part of the opening is opened

first and closed last so that there is no danger of the water in the lower part of the radiator freezing as this part of the radiator is the last to be uncovered and the first to be covered.

It is thought from the foregoing description that the advantages and novel features of my invention will be readily apparent.

I desire it to be understood that I may 10 make changes in the construction and in the combination and arrangement of the several parts, provided that such changes fall within in the scope of the appended claim.

What I claim is:—

- 15 A radiator cover comprising a member adapted to be secured to the front face of the radiator, said member having an opening therein, a projection at the lower edge of the opening and guideways at the sides thereof, the guideways being arranged in 20 upper and lower pairs, the lower pair being of greater width than the upper pair, a pair of shutters engaging the guideways,

both shutters engaging the lower guideways when in open or in partly open position with the upper shutter engaging the upper guideways when the shutters are in closed position, a projection at the lower edge of the lower shutter for engaging the projection at the lower edge of the opening for limiting the upward movement of the lower shutter, hooks formed on the upper edge of the lower shutter and on the lower edge of the upper shutter for causing movement of the upper shutter to be transmitted to the lower shutter when the hooks engage each other, an outwardly extending part at the upper edge of the upper shutter for engaging the upper wall of the opening when the shutter is in raised position and means connected with the upper shutter for moving the same.

In testimony whereof I affix my signature.

WILLIAM C. TOELLNER.
